David H. Fetzer
BY *Edward A. Lawrence*,
his ATTORNEY.

UNITED STATES PATENT OFFICE.

DAVID H. FETZER, OF DORMONT BOROUGH, ALLEGHENY COUNTY, PENNSYLVANIA.

TROCAR.

1,215,512.

Specification of Letters Patent. Patented Feb. 13, 1917.

Application filed January 4, 1916. Serial No. 70,323.

To all whom it may concern:

Be it known that I, DAVID H. FETZER, a citizen of the United States, and residing in Dormont Borough, in the county of Allegheny and State of Pennsylvania, have invented or discovered new and useful Improvements in Trocars, of which the following is a specification.

My invention consists in new and useful 10 improvements in trocars or instruments used by embalmers for aspirating the liquids and gases from a dead body and injecting in their place an embalming fluid.

The object I have in view is the production 15 of a trocar which may be connected up with the necessary bottle to receive the liquids and gases from the body and with a second bottle containing the embalming fluid to be substituted therefor, and may then be 20 introduced into a cavity or portion of the body and be used for both aspiration and injection without requiring the removal of the trocar from its place of introduction into the body.

25 For the accomplishment of this purpose, I provide a trocar which comprises a metal tube whose one end is provided with a removable sharp inserting point and whose other end is bifurcated to provide two 30 branches which are connected, respectively, to a receiving bottle for the body liquids and gases and a second bottle containing a supply of embalming fluid to be injected into the body. A two-way valve is located 35 at the juncture of the two branches with the body of the trocar so that either branch may be connected with the main bore of the trocar or both of said branches may be cut off from said bore and from each other.

40 In the accompanying drawings, Figure 1 shows in plan my improved trocar connected up with the receiving bottle and the embalming fluid bottle, ready for service; Fig. 2 is a broken horizontal section of the trocar, on enlarged scale, taken along the line II—II in Fig. 1; Fig. 3 is a section of the trocar taken along the line III—III in Fig. 2 illustrating the trocar connected to the embalming fluid bottle for the injecting operation; Fig. 4 is a similar view illustrating the trocar connected to the receiving bottle for the aspirating operation, and Fig. 5 is a similar view showing the trocar cut off from both the receiving and embalming fluid bottles and said bottles cut off from each other.

The following is a detailed description of the drawings.

A is the trocar proper, comprising a metal tube having a sharpened end piece 1 attached thereto by threaded engagement, so 50 that when said end piece becomes dull a fresh one may be substituted. The bore 2 of the trocar extends rearwardly and connects with a cylindrical, preferably tapered, valve seat 3 from which lead the two branch 65 tubes 4 and 5. 6 is a valve plug adapted to rotate in seat 3 and provided with a transverse valve port 7 of substantially the contour shown, which, when the valve plug is turned to the proper position, may either 70 connect the bore 2 of the trocar with the branch 4, as shown in Fig. 4; or connect said bore with the branch 5 as shown in Fig. 4; or may completely seal said bore and said branches from each other, as shown in Fig. 5. 75

The branch 4 is connected by a rubber tube 8 with a suction pump 9 which is in turn connected by a rubber tube 10 with a receiving bottle B, while a rubber tube 11 connects the branch 5 with a bottle C which 80 holds a supply of embalming fluid. 12 is a forcing bulb introduced in the tube 11 to withdraw the contents of the bottle C and inject the same through the trocar into the dead body.

85 By preference, as shown in the drawing, the aspirating branch 4 is a straight continuance or extension of the trocar-bore 2. This construction I have found by experiment to be important; for a tortuous passage for the withdrawal of the fluid and semi-fluid contents of the body, mixed with lumps of solids, is decidedly objectionable, since deposits collect in the bends of such a tortuous passage, interfering with a free 90 and unobstructed passage therethrough, with the consequence that such passage has not only to be cleaned frequently, but is difficult to clean.

95 A marked and salient advantage is gained 100 by the employment of a single two-way valve disposed at the juncture of the two branches 4 and 5 with the main bore 2 of the trocar, rather than by the employment of two valves, one located in each of said branches; 105 because, in the latter construction, there is, necessarily, a dead end or cul-de-sac in the embalming-fluid branch during the aspirating process to withdraw the body-contents, which dead end soon becomes filled with 110

semi-solid matter withdrawn from the body, and which cannot be dislodged by the pressure of the embalming fluid in the injecting operation, so that the trocar must be disconnected from the body to allow a cleaning wire or ram-rod to be run therethrough to open up the passage. This grave disadvantage and defect are obviated in my invention by the use of a single two-way valve disposed at the junction of the two branches 4 and 5 with the bore 2 of the trocar.

Additionally, the use of two valves, one in each branch 4 and 5, would be objectionable, as more manual operations are required in the use of such a device, as each valve has to be manipulated. With my device, there is but a single valve to manipulate, thus not only simplifying the structure and the cost of production thereof, but, also, reducing the number of manual acts required by the operator in the use thereof.

The method of using my improved trocar is as follows.

The sharpened end piece 1 is inserted into a cavity or other portion of the dead body 25 and the valve 6 is turned into the position shown in Fig. 4. The suction pump is now operated to withdraw or aspirate the liquids and gases from the body into the bottle B. The valve 6 is then turned into the position shown in Fig. 3 and by means of the bulb 12 the embalming fluid from the bottle C is injected into the body. The valve 6 is then turned into the position 35 shown in Fig. 5 and the trocar removed from the body.

The use of my improved trocar is attended by numerous advantages. When using the ordinary trocar two insertions of 40 the same into the body are required. After the first insertion and the aspirating operation, the trocar is withdrawn and disconnected from the receiving bottle. The embalming fluid bottle is next connected to

the trocar and the latter again inserted into the body. It is, of course, highly desirable that the embalming fluid be introduced at the same point at which the body liquids and gases are withdrawn, and this is difficult where two insertions are required.

When my improved trocar is used but one insertion is necessary, and the time now consumed and the trouble incurred in withdrawing and reinserting the trocar and in disconnecting it from the receiving bottle and connecting it with the embalming fluid bottle are saved.

Notwithstanding, the additional advantages of my trocar, the same is of simple and inexpensive construction and the extra 60 weight is so slight as to be negligible. The instrument takes up no more room in the embalmer's satchel than the trocar now in general use.

All the connections are made directly to 65 the trocar, requiring no additional rubber tubing nor the introduction into the tubes of numerous valves or fittings.

What I desire to claim is:

A trocar comprising a straight tubular 70 body, one end of which is formed for engagement with a removable puncturing end-piece, and the other end of which is bifurcated to provide two branches, the bore of one of said branches forming a straight extension of the bore of said body, and a rotatable two-way valve at the junction of said branches with said body, and having a diametric port therethrough, the valve being rotatable to bring said port in alinement 75 with the bore of said body and with the bore of said extension, providing an unobstructed passage through said body, extension, and valve, whereby a straight cleaning-rod may be projected therethrough.

Signed at Pittsburgh, Penna., this 31st day of December, 1915.

DAVID H. FETZER.
